UNITED STATES PATENT OFFICE

EDWARD PIERSON, OF CALUMET CITY, ILLINOIS.

CLASP.

Application filed February 17, 1925. Serial No. 9,855.

This invention relates to clasps.

An object of this invention is to provide a clasp of an improved character, and one which may be used not only as a clasp but 5 will replace the use of buttons.

A further object of this invention is to provide an improved fastening device which is easily attached to the clothing or other element to be fastened, and which is provided with a large sewing area, and which may be affixed in such a manner that even in light fabrics a relatively great stress may be had.

With the foregoing and other objects in 15 view I have invented the device shown in the accompanying drawings, in which:

Figure 1 is a top plan view of my clasp element fastened together.

Figure 2 is a top plan view of one of the 20 clasp members.

Figure 3 is a bottom plan view of the other clasp member.

Figure 4 is a section at 4—4 Figure 1.

Like reference characters indicate like 25 parts throughout the several views of the drawings and in the specification, in which 2 indicates one of the clasp members, and 3 indicates the other of the clasp members. Clasp member 2 is provided adjacent the end 30 with a bottom or knob 4, and the clasp member 3 has stamped out a pair of side walls 5 and 6 forming a channel 7 for the knob 4, and has also stamped out an end wall 8

for limiting the movement of the knob 4. Suitable holes 9 are provided near the edge 25 of the elliptical plates of both the members 2 and 3 for sewing to the garment or other member to be clasped.

In operation, the knob 4 is inserted at the reverse end of the channel 7 to that where 40 it is positioned in Figure 1, and slides down the channel reaching the limit of its movement by the end wall 8, where it is firmly held, so that the side walls 5 and 6 overhang 45 the knob 4 preventing its displacement, and the length of the channel prevents its escaping from the channel by accidental or other stresses in a backward direction.

The walls 5 and 6 are pressed up from metal pushed out in forming the channel 7, 50 and are arcuately formed as at 9, providing an arcuate channel for the button head 4.

I claim:

In combination; a pair of plates provided 55 with sewing perforations peripherally disposed, one of the plates provided with a key-hole slot, the keyhole slot provided with a channel formed by bending the metal into opposing arcs the metal being pushed out 60 in forming the keyhole slot, the other plate provided with a knob, the arcs adapted to receive and retain the knob when inserted from the side of the first plate opposite to that of the struck up portions.

EDWARD PIERSON.
